UNITED STATES PATENT OFFICE.

CHARLES C. NEWTON AND ELLIS J. HANNUM, OF PHILADELPHIA, PENNSYLVANIA, ASSIGNORS TO THE NEWTON MACHINE TOOL WORKS, INCORPORATED, OF SAME PLACE.

RADIAL PLANING-MACHINE.

SPECIFICATION forming part of Letters Patent No. 658,277, dated September 18, 1900.

Application filed April 13, 1900. Serial No. 12,772. (No model.)

To all whom it may concern:

Be it known that we, CHARLES C. NEWTON and ELLIS J. HANNUM, citizens of the United States, and residents of Philadelphia, Pennsylvania, have invented certain Improvements in Radial Planing-Machines, of which the following is a specification.

The object of our invention is to so construct a planing-machine that it will plane curved surfaces, especially those struck from a common center—such, for instance, as the saddles of locomotive cylinder-castings.

While the machine is particularly adapted to planing the saddles of locomotive cylinder-castings, it can be used for any purpose where it is desired to plane a curved surface.

In the accompanying drawings, Figure 1 is a perspective view of our improved radial planing-machine. Fig. 2 is a plan view. Fig. 3 is a side view. Fig. 4 is a vertical sectional view on the line 4 4, Fig. 2. Fig. 5 is a view on the line 5 5, Fig. 4. Fig. 6 is a plan view of the base with the standard removed, and Figs. 7 and 8 are views of details of the machine.

A is the base of the machine, on which is mounted the standard B, carrying the head C, on which the cutting-tools are mounted.

A' is a bed on which the work to be planed is placed. This bed has a series of transverse grooves a, which receive bolts for securing the work to the bed. On the bed are supporting-tables D, (two in the present instance,) made in three sections, the first section d of each table being secured to the bed A' by clamp-bolts which extend into the grooves a, and on this section d is mounted a section d', which slides longitudinally thereon. A feed-screw d³ is used for adjusting the section d'. On the section d' is a section d², mounted to slide transversely thereon and fed by means of a feed-screw d⁴. By arranging the tables in this manner they can be readily adjusted to accurately support the cylinder-casting or other article to be planed. We have shown by dotted lines in Fig. 2 the cylinder-castings of a locomotive in which the two cylinder-castings are secured together, forming a com-

plete saddle, and this is one of the articles which our invention is especially designed to plane.

On the base A is mounted a circular platform E, and on this platform are ways e e for the standard B, which is moved by a feed-screw e'. By adjusting the screw the standard can be moved on the platform and the tool moved toward or from the center of rotation of the platform.

The head C slides on guides b b on the standard B and has a nut, with which engages the vertical screw b' for raising and lowering the tool. This screw b' is connected to a hand-shaft b² through chain gearing b³ and intermediate shaft b⁴, so that on turning this shaft the head C can be adjusted vertically. On the head is a swiveled tool-carrier C', carrying the tool-clamp c, of any suitable form. The screw-shaft b' is geared to a rearwardly-extending shaft B', mounted in bearings on the base of the standard B, which has an arm b⁵ connected to the shaft by ratchet mechanism. (Shown in Fig. 5.) This arm strikes the adjustable blocks f, one on each side of the center line, and these blocks are adjustable in a radial slot a' in the base A. By this arrangement the vertical feed of the tool is provided for.

The ratchet mechanism is constructed as clearly shown in Figs. 7 and 8. The shaft B' is splined, and arranged to slide on the shaft, but turn with it, is a ratchet-wheel s, confined longitudinally on the shaft by collars s', secured to the shaft by set-screws. The arm b⁵ is carried by shoulders on the ratchet-wheel and has a spring-pawl s², which engages the teeth of the ratchet-wheel, so that it will feed the shaft B' only in one direction, one block f causing the pawl-arm to feed and the other block returning the arm to its original position.

Motion is imparted to the standard B through the driving-shaft I, on which are the pulleys i i' i''. This driving-shaft is geared to the shaft I', on which is a worm I², geared to a worm-wheel J, secured to the under side of the circular platform E, as shown clearly.

in Fig. 4. The hub of this worm-wheel extends into a suitable bearing A² in the base A of the machine, and the rim of the wheel also fits snugly in the upper portion of the base, as shown in Fig. 4.

5 In order to shift the belt at the proper time to reverse the lateral movement of the platform E, carrying the standard B and its cutting-tool, we mount on the edge of the platform lugs or projections e². In the present instance these lugs are secured in place by T-headed bolts, which enter a T-headed slot cut in the periphery of the circular platform, so that the lugs can be adjusted to any point 15 desired, and thus the radial movement of the tool is regulated.

A lever E' is pivoted at e³ to the base of the machine, and one arm of this lever is in the path of the lugs or projections e², so that 20 it will be struck by either one of the projections, as shown in Fig. 6. The other arm of the lever E' is connected to the rod e⁴, which in turn is connected to a lever G, pivoted to the belt-shifter G', having arms which shift 25 the belts from the fast to the loose pulleys. Thus, as shown in Fig. 6, one projection e² is in the act of striking the lever E' and will shift the belts, so that a reverse motion will be immediately given to the platform E, and 30 this motion will continue until the other lug e² will strike the lever on the opposite side and will again shift the lever and the belts, so that it will be seen that by shifting the lugs on the platform more or less radial movement can be obtained.

35 The operation of the machine is as follows: If, for instance, a locomotive cylinder-saddle is to be planed, the supporting-tables D are adjusted on the bed A in proper position 40 to receive the cylinder, as shown by dotted lines in Fig. 2. The curved portion of the saddle is placed in proper position to be planed by the tool. The standard B is adjusted by means of the screw e', so that the 45 tool will be in position to plane the saddle on the proper radius. The projections e² are adjusted on the periphery of the platform E, so that the belts will be shifted as soon as the tool finishes its work at each stroke and 50 the blocks f f are adjusted in the radial slot, so as to feed the tool forward at the end of each stroke. The machine is then set in motion and the entire surface of the circular portion of the saddle will be planed off on 55 proper lines, accomplishing by machinery what usually has been done by hand.

We claim as our invention—

1. The combination in a planing-machine, 55 of a bed on which the work is placed, a platform mounted to turn on a base, a standard mounted on the platform and movable toward and from the work-bed, a tool-head vertically movable on the standard, means for oscillating the platform, and means for automatically moving the tool-head in the standard, substantially as described.

2. The combination in a planing-machine, of a bed on which the work is placed, a platform mounted to turn on a base, a standard on the platform, a tool-head movable vertically on the standard, driving mechanism for the platform, means for automatically reversing the driving mechanism to oscillate the platform, and means for automatically moving the tool-head as the platform is oscillated, substantially as described. 75

3. The combination in a radial planing-machine, of a base, a platform mounted thereon, means for turning the platform, shifting mechanism whereby the platform will be turned 80 first in one direction and then in the opposite direction, a standard carried by said platform, a tool-carrier mounted on the standard, feed mechanism for vertically feeding the tool-carrier, ratchet feed mechanism, and 85 fixed blocks for actuating the ratchet feed mechanism, substantially as described.

4. The combination of a base, a platform, ways on the platform, a standard, the base of the standard mounted in the ways of the platform, a screw for adjusting the standard on the ways, a tool-carrier vertically adjustable on the standard, and means for vibrating the platform and for automatically feeding the tool, substantially as described. 95

5. The combination in a radial planing-machine, of a support for the article to be planed, a platform adjacent to the support, means for vibrating said platform, a saddle adjustably mounted on the platform, a tool-carrier arranged to slide on vertical guideways on the standard, a vertical feed-screw for engaging the tool-carrier, and intermittent feed mechanism for feeding the carrier as the platform is reciprocated, substantially as described. 105

6. The combination of a bed for supporting the work to be planed, a base, a platform mounted on the base, a worm-wheel on the platform, a worm engaging the worm-wheel, lugs adjustably secured to the periphery of 110 the platform, shifting mechanism actuated by the lugs so as to reverse the movement of the platform, a standard carried by the platform, and a tool-carrier carried by the standard, substantially as described. 115

7. The combination of a base, a platform, a standard on the platform, a tool-carrier mounted on vertical guideways on the standard, a feed-screw, a shaft geared to the feed-screw, an arm hung from the shaft, pawl-and-ratchet mechanism between the arm and the shaft so that said shaft will be turned in one direction only, and adjustable blocks against which the arm strikes as the platform vibrates so as to feed the slide, substantially 120 as described.

8. The combination in a radial planing-machine, of a base, a platform, a standard, a tool carried by the standard, means for feeding the tool and means for vibrating the platform, a bed, tables on the bed, said tables being made in three sections so that they can 125

be moved and adjustably secured to the bed, with means for moving one of the sections of the table longitudinally and the other section of the table laterally, so that the tables can be adjusted to properly receive the work, substantially as described.

5 In testimony whereof we have signed our

names to this specification in the presence of two subscribing witnesses.
